INTERNAL COMBUSTION ENGINE

Albert C. Wiesmeier, Kimmswick, Mo.

Application August 22, 1936, Serial No. 97,330

8 Claims. (Cl. 123—122)

This invention relates to internal combustion engines, and more particularly to the construction of a manifold and associated parts to be used upon such engines.

5 The principal object of this invention is to provide an improved manifold for internal combustion engines, which manifold is arranged to utilize the heat from the exhaust gases for pre-heating the fuel-air mixture drawn into the 10 manifold and assisting in the vaporization thereof to such degree and extent that comparatively heavy hydrocarbon fuels, such as common furnace oil, can be successfully and efficiently used to operate such engines. Another object of the 15 invention is to provide a manifold and associated fuel supply parts for internal combustion engines in which provision is made for preheating the fuel in the carburetor to prepare the same for complete volatilization thereof in the manifold before delivery to the cylinders.

Another object is to provide a manifold and associated fuel supply parts, which manifold and parts are simple in construction and are comparatively inexpensive to make.

25 The invention consists in the manifold, and in the parts, combinations, and arrangement of parts hereinafter described and claimed.

In the accompanying drawing which forms part of this specification, and wherein like reference numerals refer to like parts wherever they occur;

30 Fig. 1 is a partially diagrammatic view showing my improved manifold and associated parts applied to a four-cylinder internal combustion engine of the marine type, the manifold being shown in horizontal section, and the carburetor and parts connecting it to the manifold being shown out of their normal positions for the sake of clarity:

40 Fig. 2 is a vertical section taken along the line 2—2 in Fig. 1, and

Fig. 3 is a horizontal section taken along the line 3—3 in Fig. 1.

In the accompanying drawing is shown a four-cylinder internal combustion engine 1 of the marine type, which engine is equipped with a manifold and associated fuel supply parts including a carburetor 3 embodying my invention. The manifold is disposed within and enclosed by 45 a tubular cylindrical water jacket 4 which is closed at the ends thereof. This water jacket extends alongside the engine block and may be mounted upon and secured thereto in any suitable manner. In the drawing, the water jacket 50 is provided with brackets 5 at the ends thereof,

which brackets have bolts 6 extending therethru and into the block for securing the water jacket thereto.

The manifold comprises a cylindrical tube 7 arranged concentrically within the water jacket 5 and called the manifold exhaust header. The front end of this exhaust header is closed; the rear end portion extends thru the end of the water jacket where it converges into an exhaust portion 8 which leads into the exhaust pipe of 10 the engine. Extending radially from the side of the exhaust header are spaced, tubular ducts 9 which extend thru the side of the water jacket facing the engine block and communicate with the respective exhaust ports 10 of the engine. 15 In the four-cylinder engine application illustrated, three exhaust ducts 9 are required; one being located adjacent to each end of the manifold, and the third substantially midway between the ends thereof. Obviously, in the case of six- 20 cylinder engines, four exhaust ducts would be required to connect with the respective exhaust parts of such engines; likewise, with other engines the number of exhaust ducts required would depend upon the number of cylinders or 25 the type of engine with which this system is utilized.

30 Mounted concentrically within the manifold exhaust header 7 is a cylindrical tube 11 called the manifold intake header. This header is closed at the ends thereof; it has a central cylindrical core tube 12 mounted concentrically within, which core tube is open at the ends thereof for permitting exhaust gases to pass therethru as indicated by arrows. Extending radially from 35 the side of the manifold intake header 11 are spaced, tubular intake ducts 13 which extend thru the side of the exhaust header, the side of the water jacket facing the engine block and communicate with the respective intake parts 40 of the engine. With the four-cylinder engine illustrated, two intake ducts are provided, one being located on each side of the middle exhaust duct approximately midway between such exhaust duct and the exhaust duct adjacent to the 45 end of the manifold. Obviously, with other engines, the number of intake ducts required would depend upon the number of cylinders as in the case of six-cylinder engines which would require three intake ducts.

50 Provided in the manifold intake header is a comparatively short radially disposed tubular duct or pass 15. This pass at its inner end opens into the central core tube extending thru the intake header and at its outer end extends toward 55

the middle exhaust duct of the manifold and has an outwardly flared mouthpiece 16 facing such exhaust duct for receiving a part of the gases coming therefrom as indicated by arrows.

5 The carburetor 3 and parts connecting it to the manifold are shown in the drawing as extending outwardly from the side of the manifold for the sake of clarity; in actual engine applications, these parts are, preferably, located and 10 mounted underneath the manifold. The carburetor 3 includes the usual bowl 17 having a lead or riser pipe 18 which extends thru the manifold water jacket 4, thru the wall of the exhaust header 7 and opens into the intake header substantially midway between the ends thereof. Inside the intake manifold on each side of the 15 riser opening is provided a series of radially disposed fins or baffles 19 which extend longitudinally from the respective sides of the riser opening to the intake ducts. The lead or riser pipe 18 is equipped with a suitable controlling valve 20 and with an air intake 21 provided with a controlling valve 22 therefor.

25 Mounted around and completely enclosing the carburetor bowl is a bowl-shaped water jacket 23. This water jacket 23 has an inlet pipe 24 communicating with the manifold water jacket 4 near the front end thereof and an outlet pipe 25 leading into the exhaust portion 8 of the exhaust header located outside the manifold water jacket. For starting the engine, the manifold is provided with a primer 26, of any suitable type, which primer communicates with fuel inlets 27 opening into the intake ducts 13 of the manifold.

35 In the manifold hereinabove described, the hot exhaust gases coming from the engine are confined to pass through the core opening of the intake header as well as completely around the outside thereof as indicated by arrows, 40 whereby the fuel-air mixture drawn into the intake header is exposed to comparatively extensive heat radiating surfaces for preheating and vaporizing such mixture completely before delivery to the cylinders. With this improved 45 manifold, an internal combustion engine can be operated successfully and efficiently with comparatively inexpensive, heavy hydrocarbon fuels, such as common furnace oil; and the manifold is comparatively simple in construction and expensive to make.

50 Obviously, the construction of the manifold and associated parts admits of considerable variations without departing from the scope of the invention; accordingly, the invention is not to be limited to the precise construction, and arrangements of parts shown and described.

I claim:

1. A manifold for an internal combustion engine comprising an exhaust header having means 55 for receiving exhaust gases from said engine, and an intake header mounted within said exhaust header and having a passageway therethru for permitting a portion of the exhaust gases to pass therethru and baffles extending from the 60 passageway to the walls of the intake header.

2. A manifold for an internal combustion engine comprising a tubular exhaust header closed at one end and forming an exhaust opening at the other end, spaced exhaust ducts extending 65 from said exhaust header and communicating with said engine, a tubular intake header which is closed at its ends mounted in said exhaust header, intake ducts extending from said intake header thru the wall of said exhaust header and communicating with said engine, a tubular

member running thru said intake header and open at its ends for permitting a portion of the exhaust gases to pass therethru and a passage extending from the tubular member through the wall of the intake header.

3. A manifold for an internal combustion engine comprising a tubular exhaust header, spaced exhaust ducts extending therefrom and communicating with said engine, a tubular intake header which is closed at its ends in said exhaust header, said intake header having spaced intake ducts which extend thru the wall of said exhaust header and communicate with said engine, a tubular core member extending thru the center of said intake header and opening at its 10 ends into the exhaust header, and a radially disposed duct provided in said intake header intermediate the ends thereof, the inner end of the duct opening into said tubular core member and the outer end opening into said exhaust header 15 adjacent to the opening therein of one of the exhaust ducts.

4. In combination, a manifold for an internal combustion engine comprising a tubular exhaust header having ducts communicating with said engine for receiving exhaust gas therefrom, and a tubular intake header mounted within said exhaust header and having intake ducts extending thru the wall of said exhaust header and communicating with said engine, said intake header having a tubular opening therethru constituting a passageway for a portion of the exhaust gas partitions extending from the outer wall of the tubular opening to the wall of the tubular intake header, and a carburetor having a lead pipe extending thru the wall of said exhaust header and communicating with said intake header.

5. In an internal combustion engine, a tubular water jacket, a manifold mounted within said water jacket comprising a tubular exhaust header having an exhaust portion extending out of said water jacket and having ducts communicating with said engine, a tubular intake header mounted within said exhaust header and having intake ducts communicating with said engine, a tubular core member running thru said intake header and forming a passageway for a portion of the exhaust gases, a carburetor associated with said manifold, said carburetor including a bowl having a lead pipe communicating with the 50 inside of said intake header, and a water jacket mounted around said carburetor bowl and having an inlet pipe communicating with the manifold water jacket and an outlet pipe leading into the exhaust portion of the exhaust header out- 55 side of said manifold water jacket.

6. A manifold for an internal combustion engine comprising a tubular exhaust header having means for receiving gases therefrom, a tubular intake header mounted in said exhaust header and having a pair of spaced intake ducts extending therefrom and communicating with said engine, a central core tube running thru said intake header, a fuel mixer supply opening into said intake header between said intake ducts, and baffles on each side of said supply opening extending radially between the core tube and the wall of the intake header and longitudinally between the sides of the supply open- 65 ing and the intake ducts.

7. A manifold for an internal combustion engine comprising an exhaust header having means for receiving exhaust gases from said engine, and an intake header which is closed at its ends 70

mounted within said exhaust header, said intake header having a central core running through it to form a passageway for a portion of the exhaust gases through the said intake header, a fuel mixer supply opening into said intake header and baffles within the said intake header extending radially between the core tube and the wall of the intake header, and said baffles forming longitudinal ducts for the passage of the fuel mixture.

8. A manifold for an internal combustion engine comprising a tubular exhaust header having ducts communicating with said engine for re-

ceiving exhaust gases therefrom, and a tubular intake header mounted within said exhaust header and having intake ducts extending through the wall of said exhaust header and communicating with said engine, said intake header having a tubular member extending through the intake header, said intake header having within it longitudinal passageways for the fuel mixture divided from each other by side walls and means for forcing a positive circulation of exhaust gas through the tubular member.

ALBERT C. WIESMEIER.
